UNITED STATES PATENT OFFICE.

WALTER C. BAKER, OF CLEVELAND, OHIO.

Y-UNION FOR TRUSSED AXLES.

SPECIFICATION forming part of Letters Patent No. 731,093, dated June 16, 1903.

Application filed March 7, 1902. Serial No. 97,128. (No model.)

To all whom it may concern:

Be it known that I, WALTER C. BAKER, a citizen of the United States, residing at Cleveland, in the county of Cuyahoga and State of Ohio, have invented certain new and useful Improvements in Y's for Tubular Trussed Axles; and I hereby declare the following to be a full, clear, and exact description of the invention, such as will enable others skilled in the art to which it pertains to make and use the same.

My invention relates to Y-unions more especially adapted for use in connection with trussed axles, the function of the union being to connect the arched member of the trussed with the axle member.

The object of my invention is to form a Y-union of the type above set forth of plate metal (preferably steel) and to form the same integral without the necessity of welding, brazing, or soldering in any manner the two members together.

A further object is the production of a Y-union which is finished to a scale and requires but very little, if any, subsequent boring, reaming, or finishing to fit the parts thereto or assemble them therein.

My invention consists in the Y-union having the above essential characteristics and formation, as will be hereinafter fully set forth and claimed.

For the purpose of illustrating my invention I have set forth in the drawings one method of constructing or forming the Y-union, which although not the only manner in which the same can be formed, it is a clear illustration of the invention.

In the drawings, Figure I is a view in end elevation of a Y-union looking at it from the outer end. Fig. II is a view in side elevation of the same looking at it from its inner side. Figs. III and IV are respectively isometric and sectional views illustrating a blank which may be employed in constructing the union and also illustrating the method which I prefer to employ to carry out my invention.

A represents the axle member or the lower arm or socket of the union, which is preferably when finished approximately uniform in diameter throughout its interior surfaces. At the outer end of the arm or member A is a cup-shaped flange A', which is preferably

formed so as to receive a separate cup-band A² and also preferably provided with lugs a a' to engage a brace-rod. (Not shown.)

B represents an arm or socket, which extends at an angle of, say, approximately forty-five degrees out from the arm or member A in the finished device. The arm or socket B is also preferably formed approximately uniform in interior and external diameter and is designed to receive and hold in position a curved trussed bar, thus holding the ends of the straight and curved tubes which form the trussed axle together. I call this member B the "arch" member.

Inasmuch as it is very essential that the Y-union for trussed axles be very strong without being too bulky, I have devised the following method of constructing the same, viz: I prefer to take a blank C of metal and press or draw it into proper contour, so that when the ends C' C² are brought together around a mandrel or otherwise it will form the arm or member A and the cup-flange A' and also, if desired, the lugs a a', as illustrated in Figs. I and II of the drawings. However, before the ends C' C² are brought together it is essential that the arm or socket B be formed from the blank C. This I accomplish, preferably, by successive operations of drawing out or stamping out, as suggested in Fig. IV of the drawings, which is accomplished in any well-known manner and by the use of suitable dies. This drawing out or stamping is preferably done by forcing the material constituting the member B at an angle of about ninety degrees to the blank C, then by another operation forcing this material at an angle of about sixty degrees, and by a further operation forcing it to an angle of approximately forty-five degrees, which is its position with respect to the member A in the finished article. This leaves the blank C in condition to be formed into the shape shown in Figs. I and II by drawing the blank into a cylindrical or tubular shape around a mandrel or otherwise and brazing or securing the free ends C' C² together. In

order that this may be accomplished more securely, I prefer that the ends C' C² be provided with interlocking dovetails c c'. After the parts are formed as suggested in Figs. I and II and where it is desired to use a brace rod

or bar to brace the end of the axle to the reach an open space D is left in the cup-shaped flange A', and hence it becomes advisable to use a separate cup-shaped or ring-shaped piece A² to act as a continuous dust-band. This separate piece A² fits snugly within the flange A' and is held in place tightly by bringing the lugs a a' together when the brace-rod is fastened between them.

10 It is to be understood that I do not wish to limit myself to exact details or steps employed in carrying out my invention, inasmuch as they may be varied without departing from my invention. For instance, both the arms

15 A B may be drawn from plate metal by means of suitable dies without the necessity of forming the article from an open blank, as hereinabove set forth.

It will be seen from the above description 20 that by forming a Y-union in the manner above set forth lightness is attained and at the same time strength on account of the material used—viz., sheet-steel preferably—and that cheapness is attained, because when the 25 article is finished subsequent boring for fitting becomes unnecessary and the manipulation of the Y-union is reduced to a minimum.

What I claim is—

1. A Y-union made from a single blank of 30 metal and consisting of an axle member and

an arch member extending at an angle of approximately forty-five degrees to the axle member, a cup-flange made integral with the axle member, and outwardly-extending lugs carried by said flange, substantially as described.

2. As a new article of manufacture, a Y-union made from a single blank of metal and consisting of an axle member, a cup-flange integral with one end of the axle member, and an arch member integral with the axle member and extending therefrom at an angle of approximately forty-five degrees, substantially as described.

3. A Y-union consisting of a tubular axle 45 member, a cup-flange integral with one end of the axle member, lugs integral with the cup-flange, a cup-band within the cup-flange, and an arch member integral with the axle member and projecting therefrom at an angle 50 of approximately forty-five degrees, substantially as described.

Signed by me at Cleveland, county of Cuyahoga and State of Ohio, this 2d day of February, 1902.

WALTER C. BAKER.
